UNITED STATES PATENT OFFICE.

NICHOLAS C. POWERS, OF CHICAGO, ILLINOIS.

TEMPLATE FOR TRIMMING THE NECK.

Application filed June 19, 1924. Serial No. 720,917.

To all whom it may concern:

Be it known that I, NICHOLAS C. POWERS, a citizen of the United States, and a resident of Chicago, in the county of Cook and State of Illinois, have invented certain new and useful Improvements in Templates for Trimming the Neck, of which the following is, when taken in connection with the drawing accompanying and forming a part 10 hereof, a specification.

This invention relates to a machine or device by means of which the hair on the back of the neck and head can be cut or trimmed on determined lines by the party 15 using the machine or device, or by other parties not skilled in hair cutting or trimming.

Among the objects of the invention is to obtain a guide or shield which may be 20 readily placed in position for trimming or cutting the hair to the contour lines of the template, by the person using the same, as where a razor is used for shaving the back of the neck, or by other persons, as in cases 25 where a child's hair is to be trimmed by shears, by its parent. An additional object is to obtain a template of the kind named which can be used by persons whose heads vary in size. An additional object is to 30 obtain a template of the kind named which is simple in construction, durable, not liable to become broken or to get out of order, and which is economically made.

I have illustrated a template embodying 35 the invention in the drawing referred to, in which—

Fig. 1 is a rear elevation of the head of a person using the template, showing said template in elevation, in position for use.

40 And Fig. 2 is a top plan view of a template embodying the invention.

A reference character applied to designate a given part indicates said part throughout the several figures of the drawing wherever 45 the same occurs.

1 represents the template, preferably made of sheet rubber, felt, or cloth. 2, 2, represent the contour lines of one side of the template, said side being used where what is termed a round trim or cut of the hair, is desired. 50 3, 3, represent the contour line of the opposite side of the template, which is used when what is termed a square trim or cut is desired. 4, 4, represent apertures in template 1. 5, represents an elastic band, 6 represents a buckle on one end of band 5,

and 7 represents a loop on the band adjacent to the buckle 6. 8 represents the end of the band 5 which is engaged with the buckle 6, to adjust the band to the head of the person using the machine or device; that portion of end 8 which extends beyond the buckle 6, when the band is adjusted, is extended through loop 7, in the ordinary way of using buckles for attaching one end 65 of a belt to the opposite end thereof.

The band 5 is attached to template 1 by passing, extending or threading the end 8 of the band through the apertures 4, 4, substantially as illustrated in the drawing. 70

In Fig. 1 the machine or device is illustrated as adjusted and placed on the head of a person so that the contour line 2, 2, is in position to form a guide for the cutting or trimming of the hair to obtain a 75 round trim or cut. To place the machine or device so as to form a template or guide for what is termed a square cut or trim the position of contour lines 2, 2, and 3, 3, as illustrated in Fig. 1, is reversed, so that 80 the contour line 3, 3, is in the same relative position to the head and neck that contour line 2, 2, occupies as illustrated in Fig. 1.

To obtain what is termed a feather edge 85 trim or cut one of the contour lines of the template is made to correspond with the contour line of said feather edge trim.

This template is usable by men and children, and also by women and girls having short or "bobbed" hair. One of the 90 principal uses to which the invention is designed to be put is to enable a parent to cut the hair of a child and obtain a desired and regular contour line at the back of the head and neck; and this is attained by 95 adjusting the machine or device on the head of the child so that by cutting or trimming the hair close to the contour line thereof the cut is determined and controlled.

This template permits a travelling man, 100 or a man in a place remote from a barber shop to use a razor, particularly a safety razor, on the back of his own neck and obtain a regular and desired contour line.

To use the device or machine the band or belt 5, which is preferably made of elastic material, as for instance woven material having rubber therein, and known as flat elastic, is adjusted as by means of buckle 6, so that said band is put under tension when 105 the machine or device is placed and adjusted on the head. By this adjustment the 110

contour line of the lower edge or side of the template 1 is brought into close contact with the back of the head and neck. The hair below said contour line may be cut 5 closely thereto, by scissors, clippers, shears, or razor, as preferred, or required. When a person using the template desires to operate the cutting or trimming instrument a safety razor is preferably used.

10 I claim:

A template for cutting and trimming hair, comprising a body of flexible material provided with contour lines on opposite side

edges thereof corresponding with the selected cut or trim desired, in combination 15 with an elastic band by means of which said body is secured in an adjusted position relative to the back of the head and neck of a person, said body provided with apertures and said band attached to said body 20 by being extended through said apertures.

NICHOLAS C. POWERS.
